(57) **CLAIM**

The ornamental design for a notebook computer with bendable cover and screen, as shown and described.

DESCRIPTION

FIG. 1 is a perspective view of a notebook computer with bendable cover and screen showing our new design with the display opened and the cover and the screen of the display bent;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof with the display slightly closed and the cover and the screen of the display flattened;

FIG. 9 is a front view thereof with the display slightly closed and the cover and the screen of the display flattened;

FIG. 10 is a perspective view thereof with the display fully closed and the cover of the display flattened;

FIG. 11 is a front view thereof; and,

FIG. 12 is a cross-sectional view taken along line 12-12 in FIG. 11.

The dashed broken lines illustrate portions of the notebook computer with bendable cover and screen and form no part of the claimed design. The dot-dashed broken lines in FIGS. 1, 2, 6, 8, 9 and 12 define the bounds of the claimed design and form no part thereof.
